DESIGN FOR A NOTE-PAD CONTAINER

Albert Kaser, Glendale, Calif.

Application June 28, 1947, Serial No. 139,989

Term of patent 7 years

(Cl. D74—1)

To all whom it may concern:

Be it known that I, Albert Kaser, a citizen of the United States, residing at Glendale, in the county of Los Angeles and State of California, have invented a new, original, and ornamental Design for a Note-Pad Container, of which the following is a specification, reference being had to the accompanying drawing, forming part thereof, and wherein:

Figures 1 and 2 are, respectively, front and side elevational views of a note-pad container embodying my new design.

I claim:

The ornamental design for a note-pad container, substantially as shown.

ALBERT KASER.
